ATTORNEY

UNITED STATES PATENT OFFICE.

GEORGE LYNDON GRIFFIN, OF STALWART, SASKATCHEWAN, CANADA.

SIGNAL BUOY.

Application filed July 6, 1922. Serial No. 573,203.

To all whom it may concern:

Be it known that I, GEORGE L. GRIFFIN, a citizen of Canada, residing at Stalwart, in the Province of Saskatchewan and Dominion of Canada, have invented new and useful Improvements in Signal Buoys, of which the following is a specification.

The object of this invention is to provide a buoy carrying a signal, or signals, of particular construction and mounted in a particular manner, the buoy being automatically released from the deck of a ship, in the event that the latter sinks below the surface, and adapted to indicate the location of the vessel.

A further object is to provide a weighted buoy to be connected to the vessel by a cable, the buoy carrying a plurality of arms extending in various directions and each mounting a reflecting device.

A still further object is to arrange the signal elements so that the tilting of the buoy in any direction will leave at least one of the signals projecting upwardly, so that it may readily be observed.

With the foregoing and other objects in view, the invention consists in the novel construction and arrangement of elements described and claimed, it being understood that modifications may be made within the scope of the claim without departing from the spirit of the invention.

In the drawings, Figure 1 shows the device in side elevation, and as connected with and floating near a submerged vessel; Figure 2 shows the buoy in vertical section,—the upper arms, in elevation, being broken away; Figure 3 shows the device in elevation, and as connected with a winding drum; Figure 4 is a top plan view of the buoy.

A drum 10 is suitably mounted on a vessel, and around this drum a cable 11 is

coiled, a short section of chain being provided at each end, these portions being designated 12 and 13. Swivel connections are shown at 14 and 15.

The buoy 16 is connected with cable 11, and is provided with a weighted lower end 19, tending to keep the buoy in an approximately vertical position except when there is considerable tension on the cable.

A plurality of arms 20 are connected with the buoy, and extend in various directions with reference thereto, each arm carrying a reflecting device 21. The reflecting surfaces make it possible to distinguish the device more clearly than would otherwise be the case, and owing to the position of the various arms 20, at least one or two of arms will project upwardly when there is sufficient tension on the cable to cause the buoy to tilt. The temporary tilting due to wave action is also provided for, and the fact that the reflecting devices, or some of them will alternately be invisible and then visible, will increase the effect desired.

A receptacle or housing 24 may be provided for the buoy.

Opposite arms 20 are connected across the top by the curved portions 20' intersecting at 25, in the manner shown. This arrangement of the arms is intended to prevent the device from becoming fouled in the rigging. The connected arms approximate yokes.

Having thus described the invention I claim:

A buoy comprising a body portion, weighted at its lower end, arms extending from said buoy in various directions, and reflecting devices carried by the arms, said arms extending over the top of the body portion and above the reflecting devices.

In testimony whereof I affix my signature.

GEORGE LYNDON GRIFFIN.
